To Inventor:
Henry Byron

UNITED STATES PATENT OFFICE.

HENRY BYROM, OF BRADFORD, PENNSYLVANIA.

GARBAGE-RECEIVER.

SPECIFICATION forming part of Letters Patent No. 433,233, dated July 29, 1890.

Application filed May 4, 1889. Serial No. 309,666. (No model.)

To all whom it may concern:

Be it known that I, HENRY BYROM, a citizen of the United States, residing at Bradford, McKean county, Pennsylvania, have invented 5 a new and useful Receptacle for Refuse or Garbage, of which the following is a specification.

Figure 1 is a front view of the receptacle. Fig. 2 is a side view of the same. Fig. 3 is a 10 back view of same.

My invention relates to the remedy of an evil which is the cause of perplexity, trouble, and disease in dwellings arising from the exhalations from garbage and refuse, which are 15 the inevitable products of housekeeping under any circumstances. My idea is to carry and retain the said garbage in a receiver-box provided with an outer hinged door, means to hold such door normally closed, and a rod 20 and treadle to open the door, from the time of its deposit therein until the time it is carried away either for destruction or for further use.

In Fig. 1 is shown the receptacle A, with the 25 hinged reception-door B closed, and the outer edge of the hinged treadle-board C, connected by rod E with movable joints G and L to said door B, the said treadle when the door is shut being elevated to an angle of about for- 30 ty-five degrees. The door B when shut is held tightly closed by means of weights K and ropes I, running over pulleys J, and through guides V to the front bar H, where it is se- curely fastened. The reception-door B is 35 opened by a downward pressure of the foot upon treadle C, as shown in Fig. 2. The slide-tray O, which consists of a sheet of metal or other smooth-polished substance flanged on two sides, is fastened to the inside of the door 40 B, so that one of the unflanged ends of the sheet comes even with the top of the inside of door B; but the lower unflanged end of sheet projects several inches beyond the lower end of the inside of door. This projection, as 45 shown in Fig. 2, is intended, for the sake of cleanliness, to surely convey the refuse through the hopper Q into the tub R without allowing any of the garbage to lodge in the aperture left between the door B when

open and the box A which would hinder a 50 perfect closing of the door.

The method of opening the reception-door by the pressure of the foot leaves both hands free to scrape garbage from vessels of any kind into the receptacle, and the moment the 55 foot-pressure is removed from the treadle the door B is automatically closed and the receptacle A is tightly sealed and cannot be left open.

This receptacle A can be used inside the 60 house or built into the side of the house with the reception-door inside and the delivery-door S outside, or it may be used separately outside and at a convenient distance upon the base D. The outside or delivery door is 65 shown in Fig. 3 as open, and this figure also shows the tub R and also the hopper Q partially exposed, as also sewer-connection P. Where sewerage is convenient, then the bottom of the tub R should be perforated, so 70 as to discharge the liquid refuse into and through sewer-connection P; but where there is no system of sewerage, then the bottom of tub should be solid, and the liquid would have to be removed through the delivery-door 75 with the solid garbage in tub R.

Fig. 3 also shows ventilator, from and through which vapors may be carried to chimney and then consumed, or may be carried up into the air to any necessary distance, 80 or the ventilator may be omitted altogether.

What I claim as my invention, and desire to secure by Letters Patent, is—

1. The combination, in a garbage-receiver, of a receiver-box with an outside hinged door, 85 means whereby said door is held in a closed position, and a rod and treadle connected to said door to open the same, substantially as described and shown.

2. The combination, in a garbage-receiver, 90 of a receiver-box provided with an outside hinged door, connections to said door passing over pulleys upon said box, and weights attached to such connections, whereby the door is held in a closed position.

3. The combination, in a garbage-receiver provided with a hinged door, of flexible connections to said door passing over pulleys and

provided with weights, a rod attached to said door, and a treadle connected to the rod, whereby the door is opened by pressure on the treadle and shut automatically when such pressure is removed.

4. The combination, in a garbage-receiver, of a receiver-box provided with an upper outside hinged door, counter-balances whereby such door is held closed, a lower outside hinged door, and a connection to the sewer, substantially as described.

5. A garbage-receiver provided with an upper outer door held to its seat by counter-balances, removable tub within said receiver, and a lower hinged door, whereby said tub may be removed and withdrawn, substantially as described.

6. In a garbage-receiver, the combination, with a removable tub in the lower part of the

receiver, and a door whereby said tub may be withdrawn, of a hopper above the tub, and an upper outer hinged door held to its seat by counter-balances, as described.

7. The combination, with the receiving-door of a garbage-receiver, of a flanged tray O, fastened to the interior face of said door and projecting beyond the lower end thereof, substantially as described.

8. The combination, with the outer door of a garbage-receptacle, of a tray O, fastened to the interior face of said door and projecting beyond the hinged end thereof, substantially as described.

HENRY BYROM.
